UNITED STATES PATENT OFFICE.

BELA G. MERRILL, OF OAK PARK, ILLINOIS.

INK-WELL COVER.

SPECIFICATION forming part of Letters Patent No. 628,107, dated July 4, 1899.

Application filed March 18, 1899. Serial No. 709,617. (No model.)

To all whom it may concern:

Be it known that I, BELA G. MERRILL, a citizen of the United States, residing at Oak Park, Illinois, have invented certain new and useful 5 Improvements in Ink-Well Covers, of which the following is a specification.

In the drawings, Figure 1 is a plan view of my improved ink-well with the lid or cover in place; Fig. 2, a vertical sectional elevation taken in line 2 of Fig. 1; Fig. 3, a bottom plan view of the cover of the ink-well, and Fig. 4 an enlarged sectional view taken in line 4 of Fig. 1.

In making my improved ink-well cover, which is intended to be adapted for use in ink-stands, school-desks, and other places where ink-wells are used, I arrange a suitable ink-receptacle A in a suitable recess in the ink-well stand, desk, or other place, and arrange 10 a cover B to inclose the opening or recess and cover and protect the ink-receptacle and prevent the ink from evaporating or becoming deteriorated through exposure or the accumulation of dust and other impurities in it from 15 the atmosphere. The cover B is intended to be fastened in place by screws, tacks, or other convenient means, as may suit the preference of the parties making or using the same. It is preferably made of metal and nickel-plated, 20 or otherwise finished in a way that will make it ornamental and prevent it from readily corroding or otherwise deteriorating. I arrange a lid C in the cover immediately over the opening to the ink-well. This lid is intended to 25 be mounted on a rock-shaft D, so that by the turning of the rock-shaft the lid will be raised and access to the ink permitted. I prefer to make the lid slightly beveled, as shown in Fig. 2, or otherwise permitted to assume and 30 maintain a position flush with the face or surface of the cover. If desired, it may rest directly upon the top of the ink-receptacle when in its down or closed position; but as to this I do not care to confine myself and shall leave 35 it to the preference or convenience of the maker or user. In order to raise the lid whenever it is desired to use ink, I extend the rock-shaft D, on which it is mounted, to one side, as shown in Fig. 3, and arrange on its end a 40 pinion d. This pinion is shown in Fig. 4 as being a full or complete pinion; but, if desired, it may be a mutilated pinion provided only with the particular number of teeth that

will be used in raising the lid the desired distance. When made in this mutilated form, 55 it is obvious that it will occupy less space than when made as a complete pinion in the way shown. I surround this pinion by a tubular push-button E, which extends up through the cover, as shown in Figs. 1 and 4, and I provide one side of the tubular push-button with holes e, which receive the teeth of the pinion and operate as a rack, so that as the push-button is pushed down the pinion will be rotated, and with it the rock-shaft D, a 60 quarter of a revolution, which will throw the lid C into an upright position. A spring F is arranged on the under side of the cover and attached to the lower or inner end of the tubular push or rack button, so as to restore the 65 button to its initial position as soon as pressure is removed from it. This will cause the lid to be automatically closed as soon as the pressure on the button is removed. This 70 spring also operates as a holder to sustain or hold the push or rack button in its up or initial position. I prefer to locate the button, 75 as shown in Fig. 1, so that as one reaches his hand holding the pen, depress the button, causing the lid to be thrown up and the ink-well opened, all at one and the same operation. As above said, the removal of the pressure will permit the lid to be thrown back 80 into its closed position, so that the ink-well is always closed, except at the moment when it is desired to replenish the pen with ink, so that all chance of leaving the well open through the carelessness or forgetfulness of 85 users is obviated. 90

What I regard as new, and desire to secure by Letters Patent, is—

In an ink-well cover, the combination of a lid, a rock-shaft on which the lid is mounted, a pinion mounted on the rock-shaft, a rack-button extending above the top of the cover adapted to be depressed by pressure for rotating the pinion and rock-shaft and raising the lid, and means for automatically restoring the rack-button to its initial position and thereby closing the lid, substantially as described. 95 100

BELA G. MERRILL.
